GRATING

Filed May 13, 1926

UNITED STATES PATENT OFFICE

MAURICE LACHMAN, OF NEW YORK, AND JOHN R. TENCH, OF WHITE PLAINS,
NEW YORK

GRATING

Application filed May 13, 1926. Serial No. 108,752.

This invention relates to metallic gratings particularly adapted for use as sidewalk or floor gratings and of the kind adapted to cover in a vault or other empty space and at the same time afford a self-supporting surface over said space for pedestrian traffic. The invention has for its principal object the production of a grating self-supporting between its edges and strength and of simplicity of construction.

The invention has reference particularly to a metal grating of the form or construction in which the tread portion consists of a web part of a rolled metal channel, said web or tread part having portions removed while the unremoved portions form connecting members between longitudinal supporting members consisting of flanges or ribs of the channel. This general construction of grating is described in my prior Patent No. 1,325,792 but in the construction therein described the whole grating consists of an integral channel bar having sufficient width and a sufficient number of longitudinal supporting ribs or members to make up the grating of the particular size desired. This construction presents difficulties not only in the way of rolling a channel member with the multiplicity of longitudinal ribs but also presents difficulty in the fact that for large sizes of grating the weight of the bar makes it difficult to handle in the rolling operation and also in transportation to the location of use.

Our present invention has primarily for its object to produce a rolled metal grating free from the said difficulties and of such character that rolled metal channel bars of standard sizes in commercial practice may be utilized and in a manner to secure a grating of any desired width and having the maximum strength in the intermediate supporting, longitudinal members projecting downward from the tread portion between the side flanges or members. To this end we propose

to employ the channel members of standard size and to assemble them side by side with the ribs in side contact, the whole being secured together to form the completed grating of any desired width and so that the contiguous or abutting ribs will together form a rib of extra strength or resistance to vertical torsion under the load. One of the ways in which these objects may be accomplished and a grating of the desired width obtained will be described in connection with the accompanying drawing.

Further objects and advantages of the invention will appear from the accompanying description.

In the attached drawing illustrating a practical embodiment of the invention:

Fig. 1 is a perspective view of one of the channel bars forming a unit of the grating.

Fig. 2 is a plan view of the grating.

Fig. 3 is a vertical section on the line 3—3 of Fig. 2.

Referring to the several figures of the drawing and more particularly to Fig. 1:

1 indicates the web member or flat top of a rolled steel channel bar of any standard size which is provided with side flanges 2 and preferably with a stiffening or strengthening rib 3 on the underside of the web member intermediate the side flanges 2. 4 indicates a plurality of buttons or projections pressed upwardly at spaced intervals out of the metal of the rib 3 on the tread side to form a non-slip tread on the upper flat surface of the web member 1 and on the side of the grating opposite that from which the ribs project and acting to prevent slipping on the grating when the channel bars are assembled together. The web members 1 are also provided with a plurality of ventilating openings 5 cut or stamped out of the metal. These openings may be of any size, shape and number and are preferably positioned on either side of the rib 3.

The completed grate as shown in Fig. 2

is made up of a plurality of the channel bars just described arranged side by side longitudinally of each other with the side flange of one bar engaging the side flange of the next succeeding bar and fastened or otherwise secured thereto by suitable bolts or rivets 6 passing through openings 7 with which said side flanges are provided.

As will be manifest, a grating of any desired width may be constructed by using the desired number of channel bars which themselves being of standard form may be rolled in the usual way and transported with facility to the place where the grating is to be erected. At this point they may be easily assembled and when assembled as described a grating of great stiffness between its supported edges will be produced owing to the fact that the contiguous ribs being firmly clamped against one another give a supporting member of double strength while at the same time the structure effectually resists any tendency to flexure under the weight supported by it over the empty space beneath. As the channel bars are standard no special machinery or tools are necessary for manufacturing the grating so that the cost of manufacture is not great.

What we claim as our invention is:—

1. A composite metallic grating for sidewalks and the like comprising a plurality of rolled channel members arranged side by side and each provided with webs cut or stamped to provide openings and connecting members by the unremoved portions of the web the outer faces of the flanges of adjoining members being engaged directly with one another over substantially the whole extent of their surfaces and means for bolting or securing said flanges firmly together to hold the engaged surfaces in firm contact and prevent buckling or bending of the composite structure in a direction transverse to the longitudinal axis of the channel members while at the same time producing a composite reinforcing longitudinal intermediate supporting member of twice the thickness of the flanges at the external edges of the grating.

2. A composite metallic grating for sidewalks and the like comprising a plurality of metallic channel members each having a web and flanges extending therefrom at its edges and a rib rising slightly from the under side of said web so as to be of less height than the side flanges, said channel members being arranged longitudinally of each other with the outer face of the flange of one member engaging against and in direct contact with the outer face of the flange of the adjoining member throughout substantially the whole extent of the outer surface of both flanges and means for clamping said flanges together with their surfaces throughout in firm contact of the next succeeding member to form composite reinforced longitudinal

supporting members of the completed grating operating likewise through their clamped engagement to stiffen the composite structure against bending or torsion on a line transverse to the longitudinal axis of the composite structure, said webs being provided with a plurality of openings therein.

Signed at New York, in the county of New York and State of New York this 12th day of May A. D. 1926.

MAURICE LACHMAN.
JOHN R. TENCH.
